GARMENT SUPPORT

Helen Klein, Tampa, Fla.

Application August 15, 1935, Serial No. 36,404

1 Claim. (Cl. 241—7)

This invention relates to a support designed for use in supporting women's strapless or beltless garments such as evening gowns, brassières, slips or the like, thereby eliminating the use of unsightly shoulder straps or belts.

An important object of the invention is to provide a brassière support of this character which will securely grip the body of the wearer, providing a backless brassière or garment support especially adapted for use with backless gowns for evening wear.

A further object of the invention is the provision of means for detachably securing the garment to the support, whereby various types of garments may be supported by means of a single supporting device.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

Referring to the drawing

Figure 1 is a perspective view illustrating a brassière mounted on the support.

Figure 2 is a rear elevational view of the brassière.

Figure 3 is a perspective view of the support.

Figure 4 is a front elevational view of one of the pads at one end of the support.

Referring to the drawing in detail, the support comprises a split band 5 constructed of yieldable material so that the split band may be opened and positioned to engage the body of the user.

At the ends of the split band 5, are padded members 6, which grip the sides of the wearer. These members 6 are provided with sockets 7 disposed on the outer faces thereof, the socket members 7 being designed to receive studs or headed members, carried by the garment to be attached to the support.

Socket members 8 are secured to the outer surface of the split band and are also designed to receive studs carried by the garment.

Rising from the split band and disposed at points intermediate the ends thereof, is an extension 9, which extension is also formed with

socket members 10 to receive studs of the garment.

While various types of garments may be supported by the device, in the present showing a brassière has been illustrated and constructed for positioning on the split band, the brassière being particularly adapted for wear with backless evening gowns.

The brassière is indicated generally by the reference character 11 and comprises curved 10 metallic members 12 to which the cloth material, of which the brassière is constructed, is secured. Stays 13 extend from the hem 14 at the lower edge of the brassière, and terminate at points adjacent to the curved members 12, providing 15 braces for the curved members 12. Studs 15 are arranged in vertical spaced relation with each other at points intermediate the ends of the brassière and are adapted to pass into the sockets 10 of the extension 9 securing the intermediate portion of the brassière, to the support, in a manner to hold the curved members 12 in position.

The studs 15 are so arranged that when the studs 15 have been positioned the studs 16 will 25 fall opposite to the sockets 8 where they may be positioned in the sockets, securing the lower edge of the brassière to the support.

The studs 17 are so arranged that they will align with the sockets 7 of the padded members 30 6, securing the ends of the brassière to the support.

From the foregoing it will be seen that due to the construction shown and described, I have provided a support for various types of garments, in which the garment will be held in perfect fitting position, without the use of shoulder straps, belts or the like.

Having thus described the invention, what is claimed is:

A garment support comprising a split band constructed of yieldable material, enlarged padded members at the ends of the split band, a member rising from the band at a point intermediate the ends of the band, socket members on the padded members and member rising from the band, and said socket members adapted to receive headed members secured to the garment positioned on the garment support.

HELEN KLEIN.
